AIR LOG

Edward V. Rippingille, Detroit, Mich., assignor to
General Motors Corporation, Detroit, Mich., a
corporation of Delaware

Application August 8, 1941, Serial No. 406,015

4 Claims. (Cl. 170—132)

This invention relates to devices having an impeller which is driven by fluid flow.

It relates especially to fluid flow meters, distance logs or odometers and the like, in which the speed at which the impeller is driven is used as a measure of the rate of fluid flow.

More specifically, it relates to impeller blades in air logs for measuring the distance which an object traverses relatively to the air.

Such instruments are desirably small and lightly constructed, with impeller blades which are conveniently sheet steel stampings.

While such instruments can be produced within reasonable tolerance limits, the blades particularly are too fragile to permit manufacture and assembly within sufficiently close limits to insure duplication of performance characteristics of the assembly, and some means of adjustment for accuracy is necessary.

The object of the invention is a means of adjusting the performance of such a device to a given standard.

A more specific object of the invention is a means of adjusting the pitch of the impeller so that the instrument will conform to the desired standard of response.

The above and other objects of the invention will be apparent as the description proceeds.

According to the invention, screw means are provided for adjusting the pitch of the impeller blade by bending deflection of its hub portion in a direction longitudinally of its supporting shaft, in a plane containing the shaft axis and normal to the center line of the impeller blade.

The drawing shows the application of the invention to an air log for measuring the distance traversed by an airplane relatively to the ambient air.

In the drawing:

Figure 1 is a view of the device in part-sectional elevation.

Figure 2 is a view on line 2—2 of Figure 1.

Figure 3 is a view on line 3—3 of Figure 1.

Figure 4 is a sectional view on line 4—4 of Figure 1.

Figure 5 is an enlarged view of part of Figure 4 showing the manner in which the pitch of the impeller blade is adjusted by bending deflection of its hub portion.

The impeller blade 1 has a hub portion 2, secured to a hub 3, on a shaft 4 which has end pivots supported in adjustable jewel bearings 5 and 6 in a housing 7 and a housing 8 respectively, which are connected together by a U-

shaped portion 10 which will not interfere with turning of the impeller blade.

That portion of the shaft 4 within the housing 7 is provided with a worm 12, engaging a worm wheel 14, on a cross shaft 15, on which there is a cam 16 which lifts the spring arm 17 of a point 18 of a contact breaker away from a stationary point 19 thereof, once for a definite number of revolutions of the shaft 4.

10 The points 18 and 19 of the contact breaker are arranged to make and break an electrical circuit through an electromagnetic counter (not shown), and since the number of revolutions of the shaft 4 is proportionate to the rate of air flow driving the impeller, the distance traversed relatively to the air by an airplane on which the air log may be mounted will be indicated by the counter reading, provided the instrument is properly calibrated. Calibration can be effected by comparison and adjustment of the device to a known standard in a wind tunnel or in any other suitable way.

As shown, the instrument is provided with only one impeller blade, and its circular hub portion 2 is secured to the hub 3 by two rivets 22 and 23, at spaced points along a line parallel to and removed from the center line of the impeller blade on one side of a plane a—b containing the shaft axis and the center line of the impeller blade, as shown most clearly in Figure 2.

The hub 3 is chamfered at 25 and scooped away at 26 to remove weight to balance the rotor assembly about the shaft axis in the manner shown best in Figures 1 and 3.

35 A screw 28 is in screw threaded engagement with the hub 3 on that side of the plane a—b of Figure 2 opposite to the rivets 22 and 23, and adjustably extends therethrough, parallel to the shaft 4, to bear against the hub portion 2 of the impeller blade.

40 The screw 28 provides for the required delicate adjustment of the pitch of the impeller blade. As shown in Figure 5, it may be screwed through the hub 3 to bend the hub portion 2 away from the hub 3 and thereby adjust the pitch of the blade.

45 A spring 30 is provided as a backing for the hub portion of the impeller blade. As shown, the spring 30 is secured to the hub 3 by the rivets 50 22 and 23 with the hub portion 2 of the impeller blade therebetween. It serves to resiliently oppose bending deflection of the hub portion of the impeller blade, to hold it against the screw 28, and to return it to its original flat position against the face of the hub 3 upon retraction

of the screw 28, in the event that the material of the hub portion of the impeller blade is insufficiently springy to assure this.

I claim:

1. In a device driven by fluid flow, a shaft, an impeller blade with a bendable hub portion extending substantially normal to the axis of said shaft on opposite sides of a plane containing the shaft axis and the center line of the impeller blade, said hub portion of the impeller blade being attached to the shaft only on one side of said plane along a line parallel to and removed from the center line of the impeller blade, and screw means on the other side of said plane for adjusting the pitch of the impeller blade by bending deflection of its hub portion about its line of attachment to the shaft.

2. The combination according to claim 1, in which the hub portion of the impeller blade is secured to a rigid hub on the shaft, the screw 20 adjusting means including a screw in screw

threaded engagement with one of said hubs and adjustably extending therethrough, parallel with said shaft, to exert a thrust on the other of said hubs, whereby the bendable hub portion of the impeller blade is bent to effect the required adjustment of the pitch thereof.

3. The combination according to claim 1 in which the hub portion of the impeller blade is secured to a rigid hub on the shaft, the screw 10 adjusting means including a screw in screw threaded engagement with said rigid hub and adjustably extending therethrough to exert a thrust on the hub portion of the impeller blade, whereby the latter is bent to effect the required 15 adjustment of the pitch thereof.

4. The combination according to claim 1 in which bending deflection of the hub portion of the impeller blade by the screw means is opposed by spring means secured to said shaft.
